UNITED STATES PATENT OFFICE.

CHRISTIAN LANGE, OF BLACK EARTH, WISCONSIN.

HAME-STAPLE.

SPECIFICATION forming part of Letters Patent No. 252,780, dated January 24, 1882.
Application filed December 10, 1881. (Model.)

To all whom it may concern:

Be it known that I, CHRISTIAN LANGE, a citizen of the United States, resident at Black Earth, in the county of Dane and State of Wisconsin, have invented a new and valuable Improvement in Hames; and I do hereby declare that the following is a full, clear, and exact description of the construction and operation of the same, reference being had to the annexed drawings, making a part of this specification, and to the letters and figures of reference marked thereon.

Figure 1 of the drawings is a representation of a side view, partly in section. Fig. 2 is a perspective of the attachment, and Fig. 3 is a cross-section.

This invention has relation to hame-staples or trace attachments for hames; and it consists in the construction and novel arrangement of parts, hereinafter fully described, and particularly pointed out in the claim.

In the accompanying drawings, the letter *a* designates one of the bars of the hames, having the transverse parallel perforations *b* made through it.

c indicates the short bar or shoulder-piece of the attachment, having on its bearing-face *d* two parallel prongs, *e*, which are designed to be passed through the perforations *b* of the hame, and are secured thereto by heading down the ends over washers. These prongs project at right angles to the bearing-face or shoulder *d*, and the latter extends on all sides from the base of the prongs in such a manner as to form a strong brace bearing against the hame, preventing the prongs from being easily broken off.

From the outer face of the shoulder-piece extend obliquely two parallel lugs, *g*, which are made broad from front to rear, and are perforated at their ends to receive the ends of the pin-bearing *h*, on which the roller *k* turns. The bearing *h* is shown to be a screw having a threaded end, *l*, and the perforation *m* of one of the lugs is threaded to engage therewith. The perforation *v* of the other lug is usually countersunk, so that the head *z* of the bearing *h* will be flush with its outer surface. This construction facilitates the attachment or detachment of trace-connections, and in cases of accident is designed to serve an important purpose, affording ready means for detaching a horse from the draft.

The shoulder-piece, its prongs, and lugs are usually made entire of one piece of metal.

The screw roller-bearing may be used in connection with lugs cast on metallic hames.

Having described this invention, what I claim, and desire to secure by Letters Patent, is—

The hame-staple consisting of the bracing shoulder-piece *c*, the parallel prongs *e*, projecting from its bearing-face *d*, the oblique perforated lugs *g*, extending from its outer face, and the roller-bearing, substantially as specified.

In testimony that I claim the above I have hereunto subscribed my name in the presence of two witnesses.

CHRISTIAN LANGE.
